Primary Examiner — Deanna L Pratt

(57) **CLAIM**

The ornamental design for a reel for metal wire, as shown and described.

DESCRIPTION

1.1 : Perspective view 1

1.2 : Perspective view 2

1.3 : Partial enlarged perspective view of 1.2

1.4 : Front

1.5 : Back

1.6 : Top

1.7 : Bottom

1.8 : Left

1.9 : Right

The thin lines in the representations represent contours only and do not illustrate an ornamentation or decoration on the surface of the product; the parts shown by means of broken lines in the reproductions of design 1 are not part of the claimed design; the dotted-dashed lines in the reproductions of design 1 show only the boundary between the part of the claimed design and the other part.
